to the art of the invention, to applicants and to the public, a full disclosure of the invention, and that they further declare that the invention of this invention is not limited to the exact form shown, and that changes in the details, and in the proportions of the parts, may be made, without departing from the spirit of the invention, and without departing from the scope of the protection claimed.

UNITED STATES PATENT OFFICE

2,460,912

BRIDLE BIT

Arthur E. Wagner and Ford E. Camp, Meadville, Pa., assignors to Plas-Tk-Bits, Inc., Meadville, Pa., a corporation of Delaware

Application September 5, 1946, Serial No. 694,878

4 Claims. (Cl. 54—6)

1

This invention is directed to improvements in bridle bits.

It is the purpose of this invention to provide a novel form of bridle bit which is humane, rugged, and inexpensive.

More specifically, it is intended to provide a unitary bit of wholly non-metallic construction.

Hitherto, it has been proposed to cover the mouthpiece of a bridle bit with a soft cushion tube of rubber composition, but such a covering is not durable and is difficult to keep clean, particularly after it has become rough and worn.

Bits have also been used in which the mouthpiece was formed of vulcanite, although this type of bit likewise has a number of disadvantages and has never been widely accepted. This is probably due to the fact that vulcanite, which is a hard rubber produced by heating caoutchouc or India rubber with sulphur, does not mold precisely, acquires a greenish tone in use and generally deteriorates in quality with age.

In making a bit of plastic composition in accordance with the teachings of the present invention there are a number of requirements to be met in order to insure an adequate substitute for the metal bits which are commonly used. A bit should be relatively light in weight, smooth, strong, durable and non-toxic with respect to the animal. In view of the continuous biting and clamping action to which the mouthpiece of a bit is subjected by a horse, it is also essential that the bit possess adequate impact strength. It is also quite desirable, if not absolutely necessary, to provide a bit mouthpiece which does not frost or chill so as to injure the tongue of a horse when used in very cold weather. From the standpoint of economy in manufacture, it is practically necessary that any non-metallic composition be moldable. As this quality is an important feature of the present invention, it will be defined with the particularity intended.

"Mold" or "molded" is used in the plastics art and in this specification to connote that the material has gone through a stage of fluidity or softness during which it has been conformed to the shape of a confining member, and caused to set in such shape.

Any thermoplastic moldable organic material used for a bridle bit should have good tensile and flexural strength, and otherwise meet the stringent requirements which have been outlined.

The applicants have demonstrated that a rigid bridle bit can be successfully produced by molding thermoplastic material and have found that

ethylcellulose, which is polymeric, combines all the requisite characteristics in a high degree. That is to say, an ethylcellulose plastic has excellent molding qualities, is relatively lightweight (specific gravity approximately 1.2), ages very slightly, is affected by sunlight, weak acids and weak alkalies but slightly, and in addition possesses unlimited color possibilities, making it easy to produce a bridle bit of any permanent color desired. Besides being resistant to ordinary ranges of temperature, the molded ethylcelluloses are very hard and strong, with low specific heat. Fillers and binders may be used in accordance with present plastic techniques.

Therefore, it is a specific object of this invention to provide a rigid, unitary bridle bit molded from ethylcellulose and having structural features which are advantageous in a bit of this character.

Other novel details and features of improvement will be pointed out in connection with the following description of a preferred embodiment taken in connection with the accompanying drawings, in which:

Fig. 1 is a front elevation of a bridle bit;
Fig. 2 is a side elevation of the bridle bit shown in Fig. 1, and

Fig. 3 is a cross-sectional view of the bit taken on the line 3—3 of Fig. 1.

In the drawings the numeral 10 refers generally to a bridle bit which is illustrated as being of the ported type. The bit 10 includes a ported mouthpiece 12 having at each end a cheek piece 14. Each cheek piece 14 is formed to provide a bridle eye 16 at its upper end, which may be flared slightly outward in order to prevent sticking the side of the horse's head. The lower ends of the cheek pieces 14, 14 are formed with rings 18, 18 to receive the bit reins.

In order to give further strength and rigidity to the bit structure it is preferable to connect the lower extremities of the cheek pieces 14, 14 with a substantial cross bar 20 which may be curved downwardly in order to provide greater clearance. As the junctures of the cross bar 20 and the cheek pieces 14, 14 are below the rein rings 18, 18, the cross bar will also serve to prevent the rein loops from swinging around to the forward side of the cheek pieces and entanglement of the cheek pieces when roping.

Additional strength is imparted to the solid bit 10 by a fillet 22 of substantial size at each end of the mouthpiece 12 at the point of juncture with the inner side of the corresponding cheek piece 14. On the outer sides of the cheek pieces

14, 14 in alignment with the fillets 22, 22 large bosses 24, 24 are molded for the purpose of further insuring adequate strength of the integral junctures between the mouthpiece 12 and the cheek pieces 14, 14.

In describing this invention one typical form of bit and its construction have been used illustratively, but it is to be understood that the principles of this invention are applicable to a large variety of types of bridle bits and that, therefore, the invention in its broader aspects contemplates any bit of similar molded construction. Therefore, this invention is not to be limited to the specific details of construction and compositions which have been disclosed, except as may be required by the scope of the appended claims.

Having thus disclosed our invention what we claim as novel and desire to secure by Letters Patent of the United States is:

1. A unitary, rigid bridle bit of solid construction composed of molded polymeric plastic and including a mouthpiece and an elongated cheek piece extending from each end of the mouthpiece and formed to provide spaced bridle and rein openings.

2. A molded, lightweight, non-toxic bridle bit of solid construction composed of plasticized ethylcellulose and including a mouthpiece and an elongated cheek piece extending from each end of the mouthpiece and formed to provide spaced bridle and rein openings.

3. A unitary, lightweight, rigid bridle bit composed of molded polymeric plastic, said bit having a mouthpiece and cheek pieces extending from each end of the mouthpiece, each cheek piece being formed to provide spaced bridle and rein openings.

4. A unitary, rigid bridle bit of solid construction composed of molded polymeric plastic, said bit having a mouthpiece and cheek pieces extending from each end of the mouthpiece, each cheek piece being formed to provide spaced bridle and rein openings, each cheek piece having a crossbar extending between the mouthpiece and the cheek piece, the crossbar being formed to provide spaced bridle and rein openings.

5. A unitary, rigid bridle bit of solid construction composed of molded polymeric plastic, said bit having a mouthpiece and cheek pieces extending from each end of the mouthpiece, each cheek piece being formed to provide spaced bridle and rein openings, each cheek piece having a crossbar extending between the mouthpiece and the cheek piece, the crossbar being formed to provide spaced bridle and rein openings, each cheek piece having a reinforcement at the juncture between the mouthpiece and the cheek piece.

6. A unitary, rigid bridle bit of solid construction composed of molded polymeric plastic, said bit having a mouthpiece and cheek pieces extending from each end of the mouthpiece, each cheek piece being formed to provide spaced bridle and rein openings, each cheek piece having a reinforcement at the juncture between the mouthpiece and the cheek piece, each cheek piece having a crossbar extending between the mouthpiece and the cheek piece, the crossbar being formed to provide spaced bridle and rein openings.

7. A unitary, rigid bridle bit of solid construction composed of molded polymeric plastic, said bit having a mouthpiece and cheek pieces extending from each end of the mouthpiece, each cheek piece being formed to provide spaced bridle and rein openings, each cheek piece having a reinforcement at the juncture between the mouthpiece and the cheek piece, each cheek piece having a crossbar extending between the mouthpiece and the cheek piece, the crossbar being formed to provide spaced bridle and rein openings, each cheek piece having a reinforcement at the juncture between the mouthpiece and the cheek piece.

ing a mouthpiece, a cheek piece at each end of the mouthpiece, each cheek piece being provided with a bridle eye adjacent its upper end and a rein opening adjacent its lower end, and a crossbar extending between the cheek pieces below the rein openings thereof.

4. A unitary, lightweight, rigid bridle bit composed of molded polymeric plastic, said bit having a mouthpiece, a cheek piece at each end of the mouthpiece, each cheek piece being provided with a bridle eye adjacent its upper end and a rein opening adjacent its lower end, and a crossbar extending between the lower extremities of the cheek pieces below the rein openings thereof, the junctures between the mouth piece and the cheek pieces being reinforced by a fillet at each end of the mouthpiece and an aligned boss on the outside of each cheek piece.
